UNITED STATES PATENT OFFICE.

FRANK T. MALICH, OF AKRON, OHIO.

RAIL-JOINT.

1,205,236.

Specification of Letters Patent. Patented Nov. 21, 1916.

Application filed July 21, 1916. Serial No. 110,447.

To all whom it may concern:

Be it known that I, FRANK T. MALICH, a subject of the Emperor of Austria-Hungary, residing at Akron, in the county of Summit 5 and State of Ohio, have invented certain new and useful Improvements in Rail-Joints, of which the following is a specification.

This invention relates to certain new and 10 useful improvements in rail joints.

The primary object of the invention is the provision of a ready means for locking together in longitudinal alinement railway rails without the employment of screws or 15 bolts, the arrangement being such as to allow a release of the joint only upon inverting the connected rails.

A further object of the device is to provide the ends of railway rails in such a manner as to coöperate with a special form of 20 slideable fish plates and locking members as to form an automatically secured joint between the said rails.

A still further object of the device is the provision of a connection for railway rails employing coöperating members with specially formed end portions upon the rails whereby the rails are locked in operative arrangement by means easy and inexpensive 25 to manufacture and employing but few parts.

In the drawings forming a part of this application and in which like designating characters refer to corresponding parts throughout the several views, Figure 1 is a side elevation of a rail joint of the present construction. Fig. 2 is a similar view with the locking plates removed. Fig. 3 is a central horizontal longitudinal sectional view 30 thereof. Figs. 4 and 5 are vertical transverse sectional views taken respectively upon lines IV-IV of Fig. 1 and V-V of Fig. 3. Fig. 6 is a perspective view of an end portion of one of the rails. Fig. 7 is a perspective view of one of the locking plates employed showing the inner side thereof. Fig. 8 is a perspective view of one of the bridge pieces. Fig. 9 is a perspective view of the opposite side of the 35 same. Fig. 10 is a view showing a portion of the members illustrated in Fig. 1 partially broken away, and, Fig. 11 is a perspective view of the locking wedge employed.

It being understood that the present device is designed for securing railway rails

operatively positioned, the same is herein illustrated in connection with two rails 20 and 21 illustrated in Fig. 1 of the drawings operatively positioned in longitudinal alinement mounted in the usual manner upon 60 transverse ties 22, securing spikes 23 being driven into the ties and overlying base flanges 24 of the rails.

In connection with the rails 20 and 21 it will be seen that the rail 21 has its web provided with a stop block 26 extending between the base flange 24 and the tread 27 thereof while the rail 20 is provided with a similar block 26' but upon the opposite side of the rail from the block 26. The webs 25 70 of each rail 20 and 21 are provided with elongated strips or guides 28 having longitudinal dove-tail grooves 29 extending throughout the upper and lower edges thereof, the said guides terminating at the said 75 blocks 26.

The guides 28 are provided with oblique slots 30 substantially mid-way of each portion thereof upon each of the rails and alining cut-out portions 31 at the tops of said 80 guides, the said slots and cut-out portions being adapted for the reception of bridge pieces 32 conforming in shape thereto and adapted for spanning the space between the two rails 20 and 21 when operatively fitted 85 within the said cut-out portions and slots as best illustrated in Fig. 2 of the drawings. The bridge pieces 32 are of substantially inverted U-shape in form having marginal 90 longitudinal grooves 33 adapted for alining with the grooves 29 of the guides 28.

Fish plates 34 are adapted to be placed over the guides and bridge pieces at each side of the joint, each of the said plates having a complementally formed recess 35 with 95 inwardly-extending flanges 36 whereby the plates may be flatly engaged with the webs 25 and slidably arranged upon the guides 28 and bridge pieces 32 with the flanges 36 fitting within the grooves 29 and 33 and in 100 which position the opposite marginal edges of the guides 28 and bridge pieces 32 will be slidably seated within the opposite valleys 37 formed by the flanges 36 as best illustrated in Fig. 4 of the drawings.

A locking wedge 38 of the form best illustrated in Fig. 11 of the drawings is positionable within a receiving socket 39 arranged in the guides 28 adjacent the blocks 26, the said wedge being held at the top of 110

the socket 39 when the plate 34 is applied, the said wedge having a shoulder 40 at such times seated upon the free edge of the lower flange 36 of the plate 34, the wedge having 5 a bottom flange 41 arranged within the lower valley 37 thereof. Each of the plates 34 is provided with a keeper notch 42 in its lower flange 36 at a point adjacent one end thereof which is opposite the closed 10 end 43 of the plate, the notch 42 being adapted to register with the socket 39 of the guide 38 upon which the plate is positioned when the opening of the plate is in engagement with the adjacent stop block 26. 15 When the plate 34 is longitudinally shifted for bringing the notch 42 in alignment with the socket 39 of the adjacent guide 28, the wedge 38 positioned within such socket 39 drops by reason of its own weight until the 20 inner substantially squared bolt portion 44 of the wedge seats within the notch 42 whereby the plate 34 is securely locked to the guide 28 preventing removal of the plate and securing the members in their 25 operative positions. The rails being securely locked in longitudinal alignment by the device as just described, a releasing of the same is only possible by overturning the rails 20 and 21 allowing each of the wedges 38 to move toward the closed ends of the 30 sockets 39 and releasing plates 34 which may then be slidably removed from the rails, the latter being entirely disconnected by thereafter removing the bridge pieces 32. 35 The plates 34 are provided with base flanges 45 positioned upon the base flanges 24 of the rails when the device is operatively arranged and at which times the spikes 23 are preferably positioned adjacent 40 the opposite ends of the said flanges 45.

What I claim as new is:—

1. A rail joint comprising in combination with aligned rails, guide strips arranged upon the webs of the said rails provided 45 with inclined slots communicating with longitudinal cut-out portions, a bridge piece seated within the said slots and cut-out portions when the device is assembled, the said strips and bridge pieces having alining 50 grooves in their upper and lower edges, and a recessed fish plate longitudinally slidable over the said strips and bridge pieces contacting within the said grooves.

2. A rail joint comprising in combination 55 with aligned rails, guide strips arranged upon the webs of the said rails provided with inclined slots communicating with longitudinal cut-out portions, a bridge piece seated within the said slots and cut-out portions when the device is assembled, the said strips and bridge pieces having alining 60 grooves in their upper and lower edges, a recessed fish plate longitudinally slidable over the said strips and bridge pieces contacting within the said grooves, a stop block 65

for the plate carried by the web of one of said rails, and an interlocking wedge arranged between the said strip and plate intermediately positioned with respect to the said bridge piece and block. 70

3. A rail joint comprising in combination with aligned rails, guide strips arranged upon the webs of the said rails provided with inclined slots communicating with longitudinal cut-out portions, a bridge piece 75 seated within the said slots and cut-out portions when the device is assembled, the said strips and bridge pieces having alining grooves in their upper and lower edges, a recessed fish plate longitudinally slidable 80 over the said strips and bridge pieces contacting within the said grooves, a stop block arranged at one end of the said strip, the said strip having a receiving socket opening at the lower edge of the strip and arranged between the said block and adjacent slot, a gravity operated wedge positionable within the said socket, the lower portion of the said plate having a keeper notch adapted for the reception of the said wedge when 85 said notch and socket are positioned in substantial alignment with each other when the said plate is operatively positioned. 90

4. A rail joint comprising rail ends having adjacently positioned webs, guide strips 95 longitudinally arranged upon the said webs having side grooves and one of the said strips having a socket opening at the bottom of the strip, a fish plate having a recessed face provided with inwardly extending upper and lower flanges arranged within the said grooves when the plate is slidably positioned upon the said strips, the lower one of said flanges having a keeper notch therein adapted for alining with the said strip 100 socket, and a gravity operated wedge arranged within the said socket and seated within the said notch when the said plate is operatively positioned. 105

5. A rail joint comprising rail ends having adjacently positioned webs, guide strips longitudinally arranged upon the said webs having side grooves and one of the said strips having a socket opening at the bottom of the strip, a fish plate having a recessed face provided with inwardly extending upper and lower flanges arranged within the said grooves when the plate is slidably positioned upon the said strips, the lower one of said flanges having a keeper notch 115 therein adapted for alining with the said strip socket, and a gravity operated wedge arranged within the said socket and seated within the said notch when the said plate is operatively positioned. the end of 120 said plate opposite the said notch being closed and in abutting engagement with one end of the said strip when the latter is operatively arranged, and a stop block at the opposite end of the said strip abutting 125 130

engagement with the inclosed end of the said plate when the latter is operatively arranged.

6. A rail joint comprising rail ends having adjacently positioned webs, guide strips longitudinally arranged upon the said webs having side grooves and one of the said strips having a socket opening at the bottom of the strip, a fish plate having a recessed face provided with inwardly extending upper and lower flanges arranged within the said grooves when the plate is slidably positioned upon the said strips, the lower one of said flanges having a keeper notch therein adapted for alining with the said strip socket, a gravity operated wedge arranged within the said socket and seated within the said notch when the said plate is operatively positioned, the said strips being provided with inclined transverse slots, and a communicating upper cut-away portion, an inverted U-shaped bridge piece seated within the said slots and cut-away portion and having opposite longitudinal grooves adapted for the reception of the said plate flanges when the latter is operatively arranged overlying the said bridge piece, and a lower flange upon the said wedge at all times arranged within the lower flange of the plate when the wedge is positioned within the plate.
7. A rail joint comprising rail ends having adjacently positioned webs, guide strips longitudinally arranged upon the said webs having side grooves and one of the said

strips having a socket opening at the bottom 35 of the strip, a fish plate having a recessed face provided with inwardly extending upper and lower flanges arranged within the said grooves when the plate is slidably positioned upon the said strips, the lower one 40 of said flanges having a keeper notch there-in adapted for alining with the said strip socket, a gravity operating wedge arranged within the said socket and seated within the said notch when the said plate is operatively 45 positioned, the end of said plate opposite the said notch being closed and in abutting engagement with one end of the said strip when the latter is operatively arranged, a stop block at the opposite end of the said 50 strip in abutting engagement with the inclosed end of the said plate when the latter is operatively arranged, the said strips being provided with inclined transverse slots, and a communicating upper cut-away portion, 55 an inverted U-shaped bridge piece seated within the said slots and cut-away portion and having opposite longitudinal grooves adapted for the reception of the said plate flanges when the latter is operatively arranged overlying the said bridge piece, and a lower flange upon the said wedge at all 60 times arranged within the lower flange of the plate when the wedge is positioned within the plate.

In testimony whereof I affix my signature.

FRANK T. MALICH.
